Primary Examiner—Robert M. Spear*Attorney, Agent, or Firm*—T P Lewandowski[57] **CLAIM**

The ornamental design for a pattern for a tire sidewall and buttress, as shown and described.

DESCRIPTION

The sole FIGURE is a side elevational view of a pattern for a tire sidewall and buttress.

In the drawings, the broken lines defining the inner bead of the sidewall and the peripheral boundary of the tire are for illustrative purposes only and form no part of the claimed design.
